(57) **CLAIM**

The ornamental design for a hunting camera, as shown and described.

DESCRIPTION

FIG. 1 is a top, front and right side perspective view of a hunting camera showing my new design;

FIG. 2 is a bottom, back and left side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of portion 9 shown in FIG. 1. The broken lines depict portions of the hunting camera that form no part of the claimed design. The dot-dash broken lines encircling an enlargement portion of the design forms no part of the claimed design.
